Servel, Inc., New York, N. Y., a corporation of
Delaware

Application January 15, 1937, Serial No. 120,698

2 Claims. (Cl. 236—99)

My invention relates to refrigeration, and has for its object to provide an improved control device for intermittent refrigeration apparatus.

The objects and advantages of my invention will become apparent from the following description and accompanying drawing forming a part of this specification, and of which Fig. 1 diagrammatically illustrates intermittent refrigeration apparatus provided with a control device embodying my invention; Fig. 2 is a fragmentary sectional view taken on line 2—2 of Fig. 1 to illustrate more clearly parts of the control device; and Fig. 3 is a fragmentary sectional view illustrating a modification of the control device shown in Fig. 1.

Referring to Fig. 1, I have shown my improved control device in connection with intermittent refrigeration apparatus comprising a generator-absorber 10 adapted to be heated by a gas burner 11 which projects its flame into the lower end of a flue 12 extending vertically upward through the generator-absorber 10. A suitable combustible gas is delivered from a source of supply through conduit 13, control device 14 hereinafter to be described, and conduit 15 to the burner 11. A small by-pass conduit 16 may be connected around the control device 14 to provide a small ignition or pilot flame at the burner 11 when the main supply of gas is shut off.

To the upper part of the generator-absorber 10 is connected a vertically extending conduit 17 which is connected at its upper end to an air-cooled condenser 18 provided with heat transfer fins 19. The condenser 18 is connected to an evaporator 20 including a loop connected to a receiver 21. The evaporator 20 and receiver 21 may be arranged in a thermally insulated storage space 22.

The refrigeration apparatus is charged with a solution of refrigerant and an absorption liquid, such as, for example, a thirty per cent solution of ammonia and water. The system operates with alternate periods of absorption of refrigerant and expulsion of refrigerant vapor. During the relatively high vapor pressure expulsion period, the burner 11 applies heat to the generator-absorber 10 whereby refrigerant is expelled out of solution. The refrigerant vapor flows upward through conduit 17 to the air-cooled condenser 18 in which it is liquefied, and the liquid refrigerant accumulates in the evaporator 20.

When the heat supplied to the generator-absorber 10 by the burner 11 is stopped, the generator cools whereby refrigerant is absorbed into absorption liquid and flows from the evaporator 20

through the condenser 18 and conduit 17 and into the generator-absorber 10. In this absorption period, which is at a reduced pressure, the refrigerant within the evaporator 20 evaporates and takes up heat thereby producing cold. When the temperature of the evaporator 20 increases to a predetermined value during the absorption period, gas is again delivered to the burner 11 to start a heating period.

In accordance with my invention, I provide the control device 14 for controlling the flow of fuel to the burner 11 whereby the alternate periods of expulsion of vapor and absorption of refrigerant are automatically regulated. The control device 14 includes a casing 23 having inlet and outlet openings formed within bosses 24 and 25 to which are connected the conduits 13 and 15, respectively. A vertical sleeve 26 is threadedly secured at its lower end to the bottom wall of the casing 23 at the outlet formed by the boss 25. A valve seat 27 is formed at the lower end of the sleeve 26 above which are located openings 28 in the wall of the sleeve.

Within the sleeve 26 is disposed a valve 29 which controls the flow of gas to the burner 11 in response to the action of thermal elements 30 and 31. The upper thermal element 30 comprises an expandable bellows which is secured at its upper end to the top of the casing at an opening 32 formed therein. The expandable bellows 30 is connected by a tube 33 to a thermal bulb 34 which is arranged in good thermal relation with a short vertically extending conduit 35 that is closed at its lower end and connected at its upper end to the upper part of the receiver 21. The lower thermal element 31 also comprises an expandable bellows which is secured at its lower end to the bottom of the casing at an opening 36 formed therein. The expandable bellows 31 is connected by a tube 37 to a thermal bulb 38 which is arranged in good thermal relation with a vertical conduit 39 connected at its upper and lower ends to the upper and lower parts of the receiver 21. The expandable bellows 30, tube 33 and bulb 34, and also the bellows 31, tube 37 and bulb 38, each constitute an expandable fluid thermostat containing a volatile fluid which increases and decreases in volume with corresponding changes of temperature.

The lower end of the upper expandable bellows 30 is adapted to bear against a lever 40 which is pivotally connected to a side wall of the casing 23. The outer end of the lever 40 is disposed above the upper end of a member 41 which is formed integrally with the valve 29. When the

expansible bellows 31 expands sufficiently, the lever 40 is caused to move downward and move the valve 29 to its closed position. A coil spring 42 is connected at its upper and lower ends to the lever 40 and the top wall of the casing 23 to retract the lever 40 when the expansible bellows 30 contracts. The tension of the coil spring 42 is adjustable from the exterior of the casing 23, as shown at 43.

- 10 The upper end of the lower expansible bellows 31 is adapted to bear against a lever 44 which is pivotally connected to the side wall of the casing 23. To the outer end of the lever 44 is secured a relatively strong leaf spring 46 which serves as 15 a pawl and engages the teeth of a ratchet wheel 47. The ratchet wheel 47 is disposed between the side walls of the hollow upper part of the member 41 and is rotatably mounted on a pin 49. Between each side wall of the hollow part of the member 20 41 and the ratchet wheel 47 is provided a non-rotatable disk 50 of the general shape shown in Fig. 1. The disks 50 are journaled on the pin 49 and are curved inwardly, as shown in Fig. 2, and frictionally engage the sides of the ratchet 25 wheel 47.
- 25 A stop 51 is provided within the casing 23 to limit the extent of upward movement of the lever 44 due to expansion of the expansible bellows 31. A coil spring 52, which is similar to the coil 30 spring 42, is connected at its upper and lower ends to the lever 44 and the bottom of the casing 23 to retract and move the lever 44 downwardly when the expansible bellows 31 contracts. The tension of the coil spring 52 is also adjustable 35 from the exterior of the casing 23, as shown at 53.

40 The operation of the control device 14 is as follows: Assuming that a heating or vapor expulsion period is in progress, the valve 29 and other parts of the control device 14 are substantially 45 in the position shown in Fig. 1, and gas flows through conduit 13, casing 23 and conduit 15 to the burner 11. During such heating period refrigerant is expelled out of solution in the generator-absorber 10, is condensed in the condenser, and collects in the evaporator 20 and receiver 21. The refrigerant condensate flowing into the evaporator 20 and receiver 21 is at a relatively high temperature, and, when the receiver 21 becomes filled 50 with liquid and liquid flows into the conduit 35, the thermal bulb 34 is heated. When the bulb 34 is heated to a temperature, such as 100° F., for example, the increase in volume of the volatile fluid causes expansion of the expansible bellows 55 30 whereby the lever 40 is moved downward such a distance that the outer end thereof is caused to bear against the upper end of the member 41 and move the valve 29 downwardly to its closed position. During this downward movement of the 60 valve 29 the lever 44 remains in its upper position against the stop 51 and the teeth of the ratchet wheel 47 slide or slip over the outer end of the leaf spring 46.

65 When gas is no longer delivered to the burner 11 and heat is no longer applied to the refrigeration apparatus, the absorption period starts, as described above, and the evaporator 20 becomes cold. The cooling of the evaporator 20 at the beginning of the absorption period causes the volatile fluid in bulb 38, tube 37 and expansible bellows 31 to become reduced in volume whereby the latter contracts and permits the spring 52 to move the lever 44 downward. With such downward movement of the lever 44, the resilient leaf 70 spring 46 causes rotation of the ratchet wheel 47

against the frictional engagement effected by the disks 50, due to the fact that the valve 29 has previously been moved to its closed position by the downward movement of the lever 40. When the lever 44 is in its lowermost position, the engagement of the resilient leaf spring 46 with the ratchet wheel 47 effectively maintains the valve 29 in its closed position. 5

The cooling of the evaporator 20 at the beginning of the absorption period also causes the volatile fluid in bulb 38, tube 37 and expansible bellows 31 to become reduced in volume whereby the latter contracts and permits the spring 42 to move the lever 40 upward. Due to the engagement of the leaf spring 46 and the ratchet wheel 47 and the downward movement of the lever 44, however, the valve 29 remains in its closed position even though the lever 40 is moved upward and the outer end thereof no longer bears against the upper end of the member 41. 20

25 After a lapse of time the ability of the refrigerant to evaporate is reduced, and, due to the low refrigerant level in the evaporator 20 and the supply of heat to the evaporator, the temperature of the evaporator rises. Upon a rise of the evaporator temperature to about 20° F., for example, the increase in volume of the volatile fluid in the expansible bellows 31 causes the latter to expand and move the lever 44 upward against the tension of the spring 52. With such upward movement of the lever 44, the valve 29 is moved upward due to the engagement of the resilient leaf spring 46 with the teeth of the ratchet wheel 47. The frictional engagement effected between the ratchet wheel 47 and friction disks 50 is sufficient to prevent the ratchet wheel from turning so that the valve 29 is effectively moved upward and away from its seat 27. This permits gas to be supplied to the burner 11 to start a heating period of the refrigeration apparatus. 30 35 40

45 Instead of forming the member 41 integrally with the valve 29 and having a positive connection therebetween, the member 41 and valve 29 may be loosely connected so that the valve 29 will not immediately move to its open position with expansion of the bellows 31 and upward movement of the lever 44. Such a modification is shown in Fig. 3 in which the lower end of the member 41 is provided with a recess 54 to receive the upper reduced end 55 of the valve 29. 50 The member 41 is provided with a slot 56 to receive a pin 57 which is fixed to the upper end 55 of the valve 29.

55 In the operation of the modification just described, the pin 57 bears against the upper end 60 of the slot 56 when the valve 29 is in its closed position. At the end of an absorption period, when the ability of the refrigerant to evaporate is reduced, the rise in temperature of the evaporator 20 causes the expansible bellows 31 to expand and move the lever 44 upward against the tension of the spring 52. Due to the loose or flexible connection provided between the valve 29 and member 41, however, the valve 29 opens only after a predetermined upward movement of the member 41. When the pin 57 contacts and bears against the lower end of the slot 56, the valve 29 is then moved to its open position with continued upward movement of the member 41. A lag of any number of degrees may be introduced at the lost motion connection of the valve 29 and member 41. 65 70 75

80 Although I have shown and described particular embodiments of my invention, it will be apparent to those skilled in the art that modifica-

tions and changes may be made without departing from the spirit and scope of my invention, as pointed out in the following claims.

What is claimed is:

- 5 1. A control device for intermittent absorption refrigeration apparatus including a control member, a plurality of thermostats, one of said thermostats being connected to operate said member in only one direction, a notched wheel frictionally journaled on said member, means including a re-

silient pawl engaging the notches in said wheel connecting another of said thermostats to said member.

2. A control device as set forth in claim 1 in which said control member comprises two parts having a lost motion connection therebetween and said wheel is journaled on one of said parts and said first thermostat is connected to operate said part.
